UNITED STATES PATENT OFFICE.

HARRY L. TURNER, OF PORTLAND, OREGON.

LOGGING ENGINE.

15,335.

Specification of Reissued Letters Patent. Reissued Apr. 11, 1922.

Original No. 1,362,373, dated December 14, 1920, Serial No. 318,668, filed August 20, 1919. Application for reissue filed July 7, 1921. Serial No. 483,058.

To all whom it may concern:

Be it known that I, HARRY L. TURNER, a citizen of the United States, residing at Portland, in the county of Multnomah and 5 State of Oregon, have invented new and useful Improvements in Logging Engines, of which the following is a specification.

It is desirable in logging engines to have the main drum so arranged that it can be 10 driven at two speeds from the same drive shaft. This is particularly true where there are other drums driven from this drive shaft because the secondary drums should be driven ordinarily at their maximum speeds 15 at all times. It is also desirable that the mechanism may be such as to permit of the change of speed of the main drum while the drum is in motion. The construction to accomplish this purpose must be rugged because engines of this type are subjected to 20 very severe use. With this invention the main drum is provided with varying speeds and the speed of the drum may be changed while in motion. The mechanism is rugged 25 and of simple construction.

The invention is illustrated in the accompanying drawings as follows:

Fig. 1 shows a plan view, partly in section, of the engine.

Fig. 2 an outline view in section on the line 2—2 in Fig. 1.

Fig. 3 a section on the line 3—3 in Fig. 1.

Fig. 4 a plan view of the steam friction actuating mechanism, partly in section.

35 The frame is made up of the side beams 1 and 2, a centrally located longitudinal beam 3 and connecting beams 4 and 5.

The engine is provided with the usual boiler 6. Engines 7 are mounted on the side 40 beams. The engines operate on the cranks 8 and operate the drive shaft 9. The drive shaft 9 is mounted in bearings 10 mounted on the beams 1, 2 and 3.

A main drum 11 is journaled on a shaft 45 12. The shaft 12 is journaled in bearings 13 in the beams 1 and 3. The drum is provided with a friction surface 14 operating against the friction blocks 15 on the gear wheel 16. A friction operating pin 17 extends into the end of the shaft 12 and may be operated by any friction actuating mechanism desired (not shown). The pin 17 operates on a cross plate 18. The plate 18 operates the drum and moves it axially on the 50 shaft so as to move the friction surfaces into engagement. A spring 19 shifts the drum

to move the friction surfaces out of engagement when the friction device operating on the pin 17 is released. The gear wheel 16 is locked on the shaft 12 by means of a key 60 20. The gear wheel is provided with an internal gear 22 and a pinion 23 meshes with the gear 22. The pinion 23 is mounted on an intermediate shaft 24. The intermediate shaft is journaled in a bearing 25 on the 65 beam 3 and is supplied with a bushing 26 which is journaled in a bearing 27 on the beam 2. Gears 28 and 29 are journaled on the shaft 24 and these gears mesh with gears 30 and 31 fixed on the drive shaft 9. The 70 gear ratio of the gears 28 and 30 differs from the gear ratio of the gears 29 and 31, the gear 30 being larger than the gear 32 and drives the gear 28 at a higher speed than the gear 29. For convenience, therefore, the 75 gears 28 and 30 are designated as the high speed gears.

A driver 32 is locked on the shaft 24 by means of a key 33. It is provided with opposing friction surfaces 34 and 35. Friction 80 blocks 36 on the gear 28 operate on the friction surface 34 and blocks 37 on the gear 29 operate on the friction surface 35. A bushing 38 is arranged on the shaft 24 and within the gear 28. This bushing is slidingly 85 mounted on the shaft 24. It is provided with a shoulder 39 by means of which pressure may be exerted on the gear 28 and consequently on the friction blocks 36. A washer 40 may be arranged between the shoulder 90 39 and the gear 28 if desired. A similar bushing 41 is arranged on the shaft 24 within the gear 29 and is provided with a shoulder 42. The bushing 41 is slidingly mounted on the shaft 24 and the shoulder 95 42 so engages the gear that when pressure is exerted on the bushing the gear may be moved axially on the shaft so as to move the blocks 37 into engagement with the friction surfaces 35. A washer 43 is provided between the shoulder and gear if desired. Springs 44 are arranged to operate on the gear 28 and move the friction blocks 34 out of engagement when released. A spring 45 moves the friction blocks 37 out of engagement when the gear 29 is released. 100 105

Operating rods 46, preferably three of them, extend through the bushings 26, 38 and 41. These rods are provided with adjusting nuts 47 which engage the bushing 110 38 and are provided with heads 48 engaging the bushing 41. It will be readily seen that

when these rods are moved in one direction they will move the blocks 37 into engagement with the friction surfaces 35, thus throwing the low speed gear into engagement and when moved in the opposite direction they will release the low speed gear and operating through the bushing 38 force the blocks 36 into engagement with the friction surfaces 34, thus throwing the high speed gear into action. Both the high and low speed gears operate in the same direction and communicate their motion through the driver to the intermediate shaft and this through the pinion 23 and gear 22 communicates the movement to the main drum. The clearance of the friction blocks may be adjusted by the nuts 47 on the rods 46.

I prefer to operate the rods through a fluid-actuated friction device, the actuating fluid being ordinarily steam from the boiler. The end of the shaft 24 is screw-threaded at 49 and a cylinder 50 is secured on this screw-threaded end. The cylinder is provided with a cover 50^a. A piston 51 operates in the cylinder. The rods 46 have the reduced ends 52 forming shoulders 53. The reduced ends extend through the piston and are secured by nuts 54. The rods extend through glands 55. It will be readily seen that as the piston is moved in either direction the rods are carried with them so as to throw in the high or low speed gear train as desired. A tube 56 extends from the outer end of the cylinder. This tube has a head 57 which secures it within the inner surface of the cover 50^a. The outer end of the tube is secured in a head 58. A steam line 59 enters the head 58 and communicates with the tube 56 so as to deliver steam to the outer end of the cylinder. The steam line is controlled by a valve (not shown). Any type of valve may be used and ordinarily may be placed in such position as to be conveniently operated by the operator. The head 58 has an extension 60 forming an annular space 61 outside of the tube 56. This extension 60 extends through a gland 62 and the annular space 61 communicates with a port 63, the port leading to the opposite end of the cylinder from that to which the tube 56 leads. A supply pipe 64 leads into the head and delivers steam to the space 61. A suitable valve (not shown) is provided for the pipe 64 as well as the pipe 59 so that steam may be admitted and exhausted from the sides of the piston so as to move the piston in either direction.

A secondary shaft 65 is journaled in a bearing 66. A gear 67 is fixed on the shaft 65. Drums 68 and 69 are mounted on the shaft 65. A driver 70 is fixed on the shaft 65 by means of a key 70^a. The driver has the friction blocks 71 and 72 adapted to engage the friction surfaces 73 and 74 on the drums 68 and 69 respectively. A thrust pin

75 extends through the end of the shaft 65 and is operated by any desirable friction device (not shown). It operates on a cross key 76, the cross key operating on a collar 77. The collar 77 communicates movement by the pin 67^a to a collar 67^b at the end of the drum 68. By moving the collar 77 endwise the drum 68 is moved axially so as to throw the friction surface 73 into engagement with the block 71. A spring 78 is provided for releasing the drum 68. A thrust pin 79 is arranged in the opposite end of the shaft 65 from the pin 75 and is operated by any convenient friction device. It operates a cross key 80. The cross key operates on a collar 81 to move the drum 69. The movement of the drum 69 throws the friction surface 74 into engagement with the block 72 when desired. A spring 82 releases the drum 69.

The drums 68 and 69 are designed to carry operating lines one of which is the trip line. The trip line handles the main line, that is to say, carries out the main line after it has been wound in on the main drum drawing in its load. In as much as this carrying out of the main line involves practically the same load in each instance the trip line should be run at a comparatively high speed and at a uniform speed. With the main line it is desirable to vary its speed, a slower speed being used to give greater power when the load requires it and to give a better control when conditions make this slower speed desirable and to give the high speed where conditions will permit it and the power of the engine is sufficient to carry the load at such high speed. It will be readily seen as above described the main drum may be given two speeds and that the speed of the drum may be changed while the machine is in motion and that this variation of the speed of the main drum does not alter the speed of the drums 68 and 69.

It will be noted that the internal gear drive of the main drum with the intermediate shaft gives a power advantage without adding to the length of the frame. With the present invention I utilize the intermediate shaft incident to this advantageous compounding structure in introducing a speed changing mechanism for the main drum. With this construction the actuating mechanism for the speed changing mechanism can be formed to act on devices on the intermediate shaft with greater simplicity than would be possible on the crank shaft. The actuating mechanism if operating from the end of the shaft must operate from one end and the present structure because of the internal gear connection at the inner end accomplishes this in a very effective way. I have, therefore, effected the compounding of the driving connection of the main drum with a variable speed device

in a very compact manner and supplied a very simple mechanism for operating the device.

Further the use of the internal gear for 5 the main drum in connection with the intermediate shaft not only gives the desired power advantage but drives the main drum in the same direction as the drums 68 and 69 which receive their motion direct from 10 the drive shaft. Consequently all cables may be wound over the tops of the drums.

What I claim as new is:—

1. In a logging engine, the combination of a driving shaft; a driven shaft; a drum 15 driven by the driven shaft; a high speed gear connection between the drive shaft and the driven shaft; a low speed gear connection between the driving shaft and the driven shaft, both connections driving the 20 driven shaft in the same direction; drivers between said gear connections and the driven shaft; clutches between the drivers and the gears; and a controlling mechanism for said 25 clutches operated from one end of the driven shaft.

2. In a logging engine, the combination of a driving shaft; a driven shaft; a drum driven by the driven shaft; a high speed gear connection between the drive shaft and the driven shaft; a low speed gear connection 30 between the driving shaft and the driven shaft, both connections driving the driven shaft in the same direction; drivers for said gear connections on the driven 35 shaft; clutches between the drivers and the gears; a bearing for the driven shaft, both clutches being on one side of the bearing; and a clutch operating rod extending from said clutches and through said bearing.

40 3. In a logging engine, the combination of a driving shaft; a driven shaft; a drum driven by the driven shaft; a high speed gear connection between the drive shaft and the driven shaft; a low speed gear connection 45 between the driving shaft and the driven shaft, both connections driving the driven shaft in the same direction; drivers for said gear connections on the driven shaft; clutches between the drivers and the gears; 50 a bearing for the driven shaft, a clutch operating rod extending from said clutches and through said bearing, said rod operating one clutch by a movement in one direction and the other clutch by a movement in the 55 opposite direction; and thrust devices operating on the rod, said devices being on the opposite side of the bearing from the clutch.

4. In a logging engine, the combination of a driving shaft; a driven shaft; a drum 60 driven by the driven shaft; a high speed gear connection between the drive shaft and driven shaft; a low speed gear connection between the drive shaft and the driven shaft, both connections driving the driven 65 shaft in the same direction; friction clutches

connecting the driven shaft with said gear connections; a bearing for the driven shaft; and means extending through the bearing at one end of the driven shaft for operating 70 said clutches.

5. In a logging engine, the combination of a driving shaft; a driven shaft; a drum driven by the driven shaft; a high speed gear connection between the drive shaft and driven shaft; a low speed gear connection between the drive shaft and the driven shaft, both connections driving the driven shaft in the same direction; a bearing for the driven shaft; a driver locked against rotation on the driven shaft and having opposing friction surfaces; friction surfaces on the gear 80 connections; and means for throwing the friction surfaces into and out of engagement to lock and release the high and low speed gear connections.

6. In a logging engine, the combination of a driving shaft; a driven shaft; a mounting for the driven shaft; a drum driven by the driven shaft; a high speed gear connection between the drive shaft and driven shaft; a low speed gear connection 90 between the drive shaft and the driven shaft, both connections driving the driven shaft in the same direction; a driver locked against rotation on the driven shaft and having opposing friction surfaces; friction surfaces on the gear 95 connections; and means for throwing the friction surfaces into and out of engagement to lock and release the high and low speed gear connections comprising devices actuated 100 from without the mounting.

7. In a logging engine, the combination of a driving shaft; a driven shaft; a drum driven by the driven shaft; a high speed gear connection between the drive shaft and 105 driven shaft; a low speed gear connection between the drive shaft and the driven shaft, both connections driving the driven shaft in the same direction; a bearing for said driven shaft; a driver locked against 110 rotation on the driven shaft and having opposing friction surfaces; friction surfaces on the gear connections; means for throwing the friction surfaces into and out of engagement to lock and release the high 115 and low speed gear connections comprising a rod extending through the bearing; and a friction device for moving the rod in the opposite direction.

8. In a logging engine, the combination 120 of a driving shaft; a driven shaft; a drum driven by the driven shaft; a bearing for the driven shaft; a high speed gear connection between the drive shaft and driven shaft; a low speed gear connection between the 125 drive shaft and driven shaft, both connections driving the driven shaft in the same direction and each having a gear journaled on the driven shaft at the same side of the bearing; a clutch for connecting the gears 130

- with the driven shaft; a bushing in said bearing; a rod extending from the clutch through said bearing; and means outside the bearing operating on the rod to set the clutch. 65
9. In a logging engine, the combination of a driving shaft; a driven shaft; a drum driven by the driven shaft; a bearing for the driven shaft; a high speed gear connection between the driving shaft and driven shaft; a low speed gear connection between the driving shaft and driven shaft, both connections driving the driven shaft in the same direction and each having a gear journaled on the driven shaft; a clutch for connecting the gears with the driven shaft; a bushing in said bearing; a plurality of rods extending from the clutch and through the bushing; and means outside the bearing for actuating said rods to actuate the clutch. 70
10. In a logging engine, the combination of a driving shaft; a driven shaft; a bearing for the driven shaft; clutch drivers fixed on the driven shaft; gears of different ratio mounted on the driven shaft; bushings slid- 75

- locking elements of said gearing with the shaft and a motor comprising a cylinder mounted on said shaft; a piston in the cylinder; ports leading to opposite sides of said cylinder, a bushing in the bearing; and means acting through the bushing connecting the motor and clutches.
19. In a logging engine, the combination of a drive shaft; a main drum; an internal gear driving said main drum; an intermediate shaft; a pinion on the intermediate shaft meshing with the internal gear; a low speed gear connection between the driving shaft and the intermediate shaft; a high speed gear connection between the driving shaft and the intermediate shaft; clutches for said gear connections; a secondary drum shaft; a secondary drum on said secondary shaft; and a gear connection between the driving shaft and said secondary drum.
20. In a logging engine, the combination of a drum; a shaft for driving said drum; a bearing for said shaft; two gears slidably mounted on said shaft, said gears being of different sizes and each forming an element of a driving connection for the drum, one connection having a higher speed ratio than the other; clutch drivers fixed on the shaft; a fluid actuated motor mounted on the shaft; and means extending through the bearing connecting said motor with said gears adapted to move one of said gears into engagement with a driver with one movement of the motor and the other gear into engagement with a driver with another movement of the motor.
21. In a logging engine, the combination of a drum; a high gear connection; a low gear connection leading to the drum; a shaft on which one gear of each connection is mounted; a clutch mechanism for locking said gears alternately with the shaft comprising drivers fixed on the shaft; a mounting for the shaft; and means having its thrust sustained by the shaft operating through the mounting for actuating said mechanism.
22. In a logging engine, the combination of a drum; a high gear connection; a low gear connection leading to the drum; a shaft on which one gear of each connection is mounted; a clutch mechanism for locking said gears alternately with the shaft; a mounting for the shaft; and means operating through the mounting for actuating said mechanism, said means operating from one end of the shaft.
23. In a logging engine, the combination of a drum; a high gear connection; a low gear connection leading to the drum; a shaft on which one gear of each connection is journaled each of said gears having a friction surface; two friction clutch elements fixed on the shaft; a mounting for the shaft;
- and means having its thrust sustained by the shaft and operating through the mounting for setting and releasing said clutches.
24. In a driving mechanism the combination of a high gear connection; a low gear connection; a shaft on which one gear of each connection is mounted; a clutch mechanism for locking said gears alternately with the shaft comprising drivers fixed on the shaft; a mounting for the shaft; and means having its thrust sustained by the shaft and operating through the mounting for actuating said mechanism.
25. In a driving mechanism the combination of a high gear connection; a low gear connection; a shaft on which one gear of each connection is journaled, each of said gears having a friction surface; two friction clutch elements fixed on the shaft; a mounting for the shaft; and means having its thrust sustained by the shaft and operating through the mounting for setting and releasing said clutches.
26. In a driving mechanism, the combination of a shaft; two friction elements locked against rotation on the shaft; two gears mounted on the shaft and having friction surfaces adapted to engage the friction elements; and a fluid actuated controlling device mounted on the shaft and having its movable element operating axially of the shaft in both directions to set said elements and surfaces alternately in engagement, said controlling device having its thrust sustained by the shaft.
27. In a driving mechanism, the combination of a shaft; two friction elements fixed on the shaft; two gears journaled and slidably mounted on the shaft, said gears having friction surfaces adapted to engage the friction elements; and a fluid actuated controlling device mounted on the shaft and having its movable element operating on the shaft in both directions to move said gears alternately into and out of engagement with the friction elements, said controlling device having its thrust sustained by the shaft.
28. In a logging engine, the combination of a drive shaft; a main drum; a drum shaft; an internal gear driving the main drum; an intermediate shaft; a pinion on the intermediate shaft meshing with the internal gear; and a variable speed gear connection between the drum and the drive shaft through the intermediate shaft, said connection comprising elements mounted on the intermediate shaft.
29. In a logging engine, the combination of a drive shaft; a main drum; a drum shaft; an internal gear driving the main drum; an intermediate shaft; a pinion on the intermediate shaft meshing with the internal gear; and a variable speed gear connection.

nection between the drive shaft and the intermediate shaft, said connection comprising elements mounted on the intermediate shaft.

30. In a logging engine, the combination 5 of a drive shaft; a main drum; a drum shaft; an internal gear driving the main drum; an intermediate shaft; a pinion on the intermediate shaft meshing with the internal gear; a variable speed gear connection 10 between the drum and the drive shaft through the intermediate shaft, said connection comprising elements mounted on the intermediate shaft, and devices mounted on the intermediate shaft for shifting the 15 connection.

31. In a logging engine, the combination 20 of a drive shaft; a main drum; a drum shaft; an internal gear driving the main drum; an intermediate shaft; a pinion on the intermediate shaft meshing with the internal gear; a variable speed gear connection 25 between the drum and the drive shaft through the intermediate shaft; a mounting for the intermediate shaft; and devices acting through the mounting controlling the connection.

32. In a logging engine, the combination 30 of a main drum; a shaft on which the drum is mounted; an internal gear driving the drum; an intermediate shaft; a pinion on the intermediate shaft meshing with the internal gear; two gear connections having different gear ratios between the driving shaft and drum through the intermediate 35 shaft, said connection comprising elements mounted on the intermediate shaft, clutch mechanism on the intermediate shaft controlling the connections; and devices for actuating the mechanism.

40. 33. In a logging engine, the combination 40 of a main drum; a shaft on which the drum is mounted; an internal gear driving the drum; an intermediate shaft; a pinion on the intermediate shaft meshing with the internal gear; two gear connections having 45 different gear ratios between the driving shaft and drum through the intermediate

shaft; a mounting for the intermediate shaft; clutch mechanism on the intermediate shaft controlling the connections; and devices acting through the mounting for actuating the mechanism. 50

34. In a logging engine, the combination 55 of a main drum; a shaft on which the drum is mounted; an internal gear driving the drum; an intermediate shaft; a pinion on the intermediate shaft meshing with the internal gear; two gear connections having different gear ratios between the driving shaft and drum through the intermediate 60 shaft; said connection comprising elements mounted on the intermediate shaft; friction clutch mechanism on the intermediate shaft controlling the connections; and devices for actuating the mechanism. 65

35. In a logging engine, the combination 70 of a main drum; a main drum shaft; an internal gear driving the main drum; an intermediate shaft; a pinion on the intermediate shaft meshing with the internal gear; a drive shaft; a two-speed gear connection between the drive shaft and the intermediate shaft; a second drum; a second drum shaft; and a direct gear connection 75 between the drive shaft and the second drum. 75

36. In a logging engine, the combination 80 of a driving shaft; a driven shaft; a drum driven by the driven shaft; a high speed gear connection between the drive shaft and driven shaft; a low speed gear connection between the drive shaft and the driven shaft, both connections driving the driven shaft in the same direction; a bearing for said driven shaft; a driver fixed on the driven shaft and having opposing friction surfaces; friction surfaces on the gear connections; and means for throwing the friction surfaces into and out of engagement to lock and release the high and low speed gear connections. 85

In testimony whereof I have hereunto set my hand.

HARRY L. TURNER.
